UNITED STATES PATENT OFFICE.

JOHN PAGE AND HARRY PAGE, OF CLEVELAND, OHIO.

MAIL-DELIVERY CHUTE.

947,843.

Specification of Letters Patent. Patented Feb. 1, 1910.

Application filed August 28, 1908. Serial No. 450,601.

To all whom it may concern:

Be it known that we, JOHN PAGE and HARRY PAGE, citizens of the United States, and residents of Cleveland, in the county of 5 Cuyahoga and State of Ohio, have invented certain new and useful Improvements in Mail-Delivery Chutes, of which we hereby declare the following to be a full, clear, and exact description, such as will enable others 10 skilled in the art to which it appertains to make and use the same.

The objects of the invention are to provide means for distributing mail throughout an office or other building in which many people 15 are congregated, and the invention specifically comprises means for delivering the mail from an upper floor to the respective lower floors, whereby the time and labor of the mail carrier or distributor ordinarily employed in visiting personally each separate 20 floor and office thereon are materially economized, and the mail is automatically delivered at the location desired.

The invention consists in a mail chute, 25 into which the mail is deposited at a high elevation, and in separately adjustable means for directing the mail to the boxes of individual occupants of the building on the various floors below.

To accomplish these objects a mail chute 30 is constructed common to all the floors of a building, and an opening for the insertion of the mail is provided upon the upper floor, so that by one visit to the upper floor, or 35 point of highest elevation of the chute, all offices below this opening can be supplied with mail without personally visiting them. Upon each floor is provided a mail box, and within the mail chute are provided pivoted 40 arms, which serve to direct the mail in turn to the exact mail boxes into which it is destined to fall, and all these directing arms are operated from a common station at the upper end of the chute.

The invention further comprises the combination and arrangement of the various parts and construction of details, as herein-after described, shown in the accompanying drawings and specifically pointed out in the 45 claims.

In the accompanying drawings Figure 1— 50 is a vertical longitudinal section from front to rear of the improved form of mail chute,

showing in the upper portion of the figure the liners for operating the delivery arms or 55 plates, and in the lower portion of the figure, one of the arms and the manner of operating it, and showing it in position for delivering the mail, and closed to mail delivery in dotted lines. Fig. 2, is a vertical 60 longitudinal section taken from one side of the chute to the other, showing operating levers and signal lights, and the side passages in which the electric wires and operating wires or chains for the delivery arms are 65 inclosed. Fig. 3, is a vertical central section through a transverse bar of the chute, showing a push button and contact devices arranged to close an incandescent lighting circuit at the moment of complete opening of 70 one of the mail delivery arms, in this manner enabling the operator to act with certainty, and to have visible assurance that the desired delivery arm has been opened, and that all others remain closed. 75

In the views, 1—is the mail chute, secured vertically to a wall 2, and provided preferably with a glass front 3, so that the mail falling therethrough is visible, and any jamming in the chute of letters, or circulars, can 80 be ascertained at once.

The mail introduced into the chute at a common opening O at the top thereof is discharged into a suitable box 4, one of which can be located on each floor of a building, and may project through the wall as shown in Fig. 1—directly into a private office or reception room. Hence every office or suite of offices in the vertical range of the chute can be supplied therefrom with ease. 85 To permit this to be done readily each box 4 is supplied with a delivery arm 5, which is pivoted at 6, in an opening 7, in the rear wall of the chute. This arm is dished or curved to direct the mail from the chute, 90 into the mail box, and when opened is adapted to lie diagonally across the chute so as to catch everything deposited therein. 95

The upper edge 8, of the arm 5, enters a recess 9, in the transverse bar 10, or wall of 100 the chute, so as not to interfere with the fall of the mail. Slight projecting lips such as shown at 11, also assist in preventing the mail from catching upon the lower edge 13, of the delivery opening. 105

If the chute is formed of joined sheet

metal sections the lips 11, can be formed at the lower edges of the superimposed sections, and be integral therewith.

A spring 12, normally serves to keep each 5 delivery arm closed as shown in dotted lines in Fig. 1, and when closed the rounded back R of each arm projects into the chute and serves to deflect and prevent letters from catching on the lower edge 13, of the delivery opening, where the delivery arm is hinged. These delivery arms are raised to place them across the chute, so as to catch the mail, by means of flexible connections such as fine cords, wires, or chains, 14, 14, 10 which traverse the side passage 15, adapted to receive them. These cords are operated to raise the arms by means of suitable levers, 16, 16, arranged upon a suitable plate 17, situated on the upper floor of the building, 15 and from whence mail can be delivered to every mail box on the floors below.

Each lever is secured when thrown to open the delivery arm, by any convenient device, such as a pawl 18, and ratchet arc 19, and 20 remains down until the arm which it controls has delivered the mail to its respective box. The flexible connections 14 can be guided into suitable directions by means of openings P in a block of wood P'. To make 25 it certain that the mail has been delivered to the right box, each lever can bear a number, and each delivery arm when opened can be made to close an electric circuit to a corresponding lamp as shown at 20, 20 Figs. 1, and 30 2. This is readily accomplished by providing a push button 21, and contacts 22, 23, adapted to be closed by the edge of the delivery arm when fully open as shown in Fig. 3. One lamp alone connected with all 35 40 the delivery arms would serve to indicate that each one had been opened, and could be used in a simpler form of apparatus.

The electric wires 24, connecting the switches and lamps are preferably carried 45 up a side passage 25, specially prepared to receive them.

26 represents a battery or other source of electricity.

Having described the invention what we claim as new and desire to secure by Letters 50 Patent is:

1. The combination with a vertically arranged chute provided at intervals with mail delivery openings, of a mail receiving box communicating with each opening, a curved 55 delivery arm pivoted in the lower edge of each opening, and adapted to lie diagonally across said chute, and to alternately close said delivery opening, an operating station, or box, at the point of highest elevation of 60 said chute, common to all said delivery arms, an operating lever therein for each of said delivery arms, flexible connections between said levers and said delivery arms, a closing spring for each arm, and a signal device 65 adapted to be operated by each one of said arms when in the open position, and in position to deliver mail.

2. The combination with a mail chute provided with mail delivery openings at intervals, of a mail receiving box communicating with each opening, a delivery arm pivoted in the lower edge of said opening, and adapted to be moved vertically to close one of said openings and to be alternately moved 70 to lie diagonally across said chute to deliver mail falling therethrough into one of said openings, recesses in the wall of said chute adapted to receive the inner ends of said arms, means for automatically moving said 75 arms to close said delivery openings in said chute, and means operated from above to incline said arms to adapt them to deliver mail through said delivery openings, the backs of said delivery arms being curved to 80 project into said chute, and serving as deflectors to prevent the mail from engaging the lower edge of said delivery openings.

In testimony whereof we hereunto set our hands this 21st day of August 1908.

JOHN PAGE.
HARRY PAGE.
